SAILBOAT FITTING

Lloyd Hornbostel, 1638 Emerson St., and John H. Franz,
1415 Chapin St., both of Beloit, Wis.
Filed Apr. 24, 1962, Ser. No. 189,799
8 Claims. (Cl. 114—111)

This invention relates to sailboat fittings and more particularly to a sailboat fitting which affords ready movement of a jib sheet or the like relative to a stay line, or the like.

In maneuvering sailing craft, it is advantageous at frequent intervals, especially during reaches or downwind runs, to pass a line such as a jib sheet from a position inside the stay line or shroud to a position outside the stay line or shroud thereby giving more effective use of the jib sail. After completion of the broad reach or downwind run it then becomes necessary to return the line such as the jib sheet to the prior position, that is, from inside the stay line or shroud whereby the jib sail is efficiently used on beam reaches, close reaches or windward maneuvers. For reasons of speed and safety, it is necessary that this be done "smartly," that is, quickly and effectively.

A number of devices have been proposed or constructed for this purpose, but none of these devices has achieved the desired result. Thus, such previous devices have been either clumsy and difficult to operate, or have been flimsy and dangerously unreliable in practice.

The present invention makes it possible to pass a line or "sheet," such as the jib sheet, outside the stay line or shroud and return in a speedy safe and effective manner and with entire certainty in operation. In accordance with the invention, an elongate ring is formed of steel wire or other material which is sufficiently strong to withstand and take the entire working load on the sheet. In operation, this ring connects upper and lower portions of the sheet, by means of eye-splices on the adjacent sheet portion ends which are slidably mounted on the ring. Thus, the inside radii of the ring are sized to accommodate the eye-splices and the eyes themselves are covered with material such as to minimize chafing, also serve to guard against corrosion in the eye-splices.

As used herein the term "stay line" will include "shrouds."

In one of the elongate sides of the ring, and preferably centered in this side, a gap is provided which is of a size large enough only to pass the mast stay into and out of the ring, but not sufficiently large to permit the eye-splices in the sheet to be removed. Thereby, when it is necessary to move the jib sheet or other sheet in relation to a stay line, the sheet may be moved up against the stay line and the stay line may be passed into the elongate ring connecting the sheet portions, through the gap in the ring. Thereupon, the ring is rotated 180° so that the gap is facing in the opposite direction to its initial position. The sheet and ring are then moved away from the stay line by passing the stay line out of the gap once again. This process may be repeated in the reverse direction for a return movement of the jib sheet or other line.

Accordingly, it is an object of the present invention to provide a sailboat fitting as described which permits passing of a line such as the jib sheet from inside the stay line and return, in a manner which is both speedy and safe, and entirely effective and reliable.

Another object of the invention is to provide a device as described which interconnects sheet portions in a manner which is very secure, but which affords relative rotation of the ring for movement of the sheet from

2

one side to another of a stay line or other such line with great facility.

Yet another object of the invention is to provide a sailboat fitting which is simple, rugged and adapted for use over long periods of time without substantial wear or corrosion.

Other objects and advantages of the invention will become apparent as the description proceeds in accordance with the drawings in which:

FIGURE 1 is a top plan view of a sailboat and of a sailboat fitting according to the present invention in operative relation on a jib sheet therefor;

FIGURE 2 is a schematic view of a mast, and stay lines which may be passed into and out of the sailboat fitting or ring of the invention in moving the jib sheet from one side to another of the staylines;

FIGURE 3 is an enlarged view, partly broken away, of an end portion of a jib sheet in connected relation with the sailboat fitting ring of the invention;

FIGURE 4 is a diagrammatic representation of the sailboat fitting in operative position and connecting upper and lower sheet portions on one side of a stay line;

FIGURE 5 is a corresponding view showing the sailboat fitting on the opposite side of the stay line after rotation of the fitting; and

FIGURE 6 is a reduced diagrammatic representation of the sailboat fitting in an intermediate rotational position.

Referring now to the drawings, a sailboat fitting 10 is shown according to the present invention which includes an elongate ring 11 and eye-splices 12 and 13 connecting front and rear portions 14 and 15 of a jib sheet or line 16. A second jib sheet or line 16a may be utilized, if desired, within the scope of the invention which includes a sailboat fitting 10a, having an elongate ring 11a and eye-splices 12a and 13a connecting front and rear portions 14a and 15a of the jib sheet or line. Thus the sheet 16a may provide ready control of the jib sail 17 from the opposite side of the boat without requiring the passing of a line around the mast.

Although jib sheets 16 and 16a are shown in the presently illustrated embodiment of the invention, other sheets and lines may also be provided with a fitting according to the invention, and different arrangements of such lines may be utilized, as understood by those skilled in the art. Also, only one jib sheet or line may be provided if desired. In the example shown, the jib sheets 16 and 16a have the front ends 13 and 13a thereof connected to a jib sail 17 secured to the deck of a sailboat 18 and to a mast 19 on the boat, as also understood by those skilled in the art. The mast 19 is supported by stay lines 20, 21 and 22 connected to an upper end of the mast and to the deck, again as understood by those skilled in the art. In maneuvering the sailboat 18, it is necessary at frequent intervals to pass the line or jib sheet 16 from one hand to the other, as for instance, in tacking or coming about in the example shown. It is further necessary that this be done "smartly" i.e., quickly and effectively, and without difficulty.

To this end, the fittings, such as 10, have the elongate rings thereof formed of steel wire or other material strong enough to take the entire working load on the sheets, e.g. sheet 16. Again referring to the fitting 10 as exemplary of the invention, the inside radii of the ring 11 are sized so as to accommodate the eye-splices 12 and 13, or other connecting means for the upper and lower line portions 14 and 15.

The elongate sides of the ring 11 are designated by reference numerals 23 and 24 respectively, and in one of the elongate sides, such as the side 24, a gap 25 is provided which may have rounded or chamfered inner and outer edges as shown and is preferably disposed cen-

trally of the length or reach 24 of the ring. The gap 25 is of a size large enough to pass the mast stays therethrough, e.g. the lefthand stay 21 in the example shown, but is small enough to prevent movement therethrough of the eye-splices 12 and 13.

In a typical example, the eye-splices will have a cross-sectional diameter approximately twice as great as the diameter of the stay lines. The stays or guide lines used in the type of craft shown in the drawings generally have a diameter of $\frac{5}{16}$ of an inch, more or less. The sheet, on the other hand, is usually a rope or cable having a diameter of not less than $\frac{1}{2}$ inch.

The eye-splices may be of a conventional type with the eye portions thereof preferably covered with a material which is effective to minimize chafing, such as hard vulcanized rubber. Such material also serves to guard against corrosion and, will of course, provide a diameter for the eye-splices somewhat greater than the diameter of the sheet.

The eye-splices 12 and 13 may be connected to the adjacent end of the sheet portions 14 and 15 in any conventional manner as understood by those skilled in the art, and the sheet portions 14 and 15, eye-splices 12 and 13 and the ring 11 together form an entirely reliable and strong sheet construction.

Referring now to FIGURES 4 and 5, in operation, and when it is desired to move the sheet 16 from one hand to another, the sheet is brought into proximate relation with the stay line, such as the stay line 21, with the gap 25 in the ring 11 on the side of the ring adjacent the stay line. The gap is brought into register with the stay line, whether manually or by operation of the sheet in the usual manner and the stay line passed into the interior portion of the ring. Once the stay line is inside the ring, the ring is manually rotated either clockwise or counter-clockwise through the eye-splice openings 26 until the reach or side 24 of the ring forming the gap 25 is in a position opposite from its initial position in approaching the stay line. Thereafter, the sheet 16 is moved away from the stay line 21 or the ring 11 is itself moved relative to the stay line to pass the stay line out of the gap 25 so that the sheet is free of the stay line, and the movement to the other hand is completed.

Although we have described the fitting of the invention with respect to a jib sheet, or other sheet on a sailboat, it will be appreciated that it has a broad range of applications in situations where a device which must maintain its structural integrity against tension stresses and the like must be passed across a line or other elongate element which would otherwise block its direct movement therewith.

Although we have herein set forth and described our invention with respect to certain specific principles and details thereof, it will be understood by those skilled in the art that these may be varied without departing from the spirit and scope of the invention as set forth in the hereunto appended claims.

We claim as our invention:

1. In a sailboat having a mast and stay line therefor, a sail, and a sheet connected to the sail for controlling the sail, a ring defining a gap sized to receive the stay line, said sheet being separated intermediate its ends, and loop means on each of the separated portions of the sheet slidably receiving the ring, said loop means and gap having a relative dimension such as to prevent removal of the loop means from the ring whereby the ring is effective to receive the stay line when moved thereagainst with the gap in register therewith and to release the stay line upon rotation of the ring through the loop means so that the sheet is disposed on an opposite side of the stay line from its initial position.

2. In a structure including an elongate, relatively fixed member and an elongate, relatively movable member, means for moving the relatively movable member past the relatively fixed member across an intersecting path

comprising a ring having a gap sized to releasably receive the relatively fixed member into said ring, said relatively movable member having a pair of separated portions, and means on each of said separated portions slidably receiving said ring, said means on each of said separated portions being sized to prevent passage thereof through said gap.

3. A line structure adapted for use with elongate members to be passed in intersecting relation comprising 10 a line having a pair of separated portions, an eye-splice on an end of each of said separated portions, a ring rotatably received in said eye-splices and a gap defined by said ring dimensioned to receive therethrough an elongate member to be by-passed by the line, said eye-splices 15 having a cross-sectional dimension such as to prevent their removal from the ring through the gap and said ring being rotatable to permit an elongate member to enter the ring through said gap when said gap is on one side of the eye-splices and permit the elongate member to 20 leave the ring through said gap when the gap is on the other side of said eye-splices.

4. In a sailboat having a mast secured by a stay line and a sail supported by the mast and having one end free relative to the mast, a bipartite sheet having one 25 portion with one end connected to the sail and the other end formed with an eye-splice, and the other portion with one end free for manual engagement and the other end with an eye-splice, an elongate ring having inner radii sized to accommodate the eye-splices and rotatably received in the eye-splices and a gap defined by the ring centrally in one elongated side thereof dimensioned to 30 prevent inadvertent release of the eye-splices from the ring and to permit entry and exit of the stay line relative to the ring, whereby the sheet may be moved to pass the ring into surrounding relation with the stay line passing through the gap, and the ring may be rotated with the stay line therein to position the gap on the opposite side of the stay line from the initial position 35 thereof so that the sheet may be moved away from the stay line by passing the stay line through the gap.

5. In a sailboat having a mast secured by stay lines and a jib sail supported by the mast and having one end free relative to the mast, a pair of bipartite sheets each 45 having one portion with one end connected to the sail and the other end formed with an eye-splice, and the other portion with one end free for manual engagement and the other end with an eye-splice, an elongate ring having inner radii sized to accommodate the eye-splices and rotatably received in the eye-splices and a gap defined by the ring centrally in one elongated side thereof dimensioned to 50 prevent inadvertent release of the eye-splices from the ring and to permit entry and exit of a stay line relative to the ring, whereby the sheet may be moved to pass the ring into surrounding relation with the stay line with the stay line passing through the gap, and the ring may be rotated with the stay line therein to position the gap on the opposite side of the stay line from the initial position 55 thereof so that the sheet may be moved away from the stay line by passing the stay line through the gap.

6. A sailboat fitting adapted to be connected slidably between separated portions of a sail sheet or the like with each of the portions having an eye splice and adapted to receive a stay line, the fitting comprising a ring formed 65 of a relatively rigid material of good tensile strength, said ring having a gap through one side thereof dimensioned to closely receive the stay line therethrough and to prevent removal of the eye splices so that the ring is effective to receive the stay line when moved thereagainst 70 with the gap in register therewith and to release the stay line upon rotation of the ring through the eye splices without releasing the eye splices and so that the sheet is disposed on an opposite side of the stay line from its initial position.

7. A sailboat fitting adapted to be connected between

separated portions of a sheet for a sail or the like with each of the portions having an eye splice and adapted to receive a stay line, the fitting comprising an elongated ring having inner end radii dimensioned to accommodate said eye splices and having a gap formed centrally in one side thereof intermediate said inner ends dimensioned to closely receive the stay line therethrough and to prevent removal of the eye splices within the ring so that the ring is effective to receive the stay line when moved thereagainst with the gap in register therewith and to release the stay line without releasing the eye splices upon rotation of the ring so that the sail sheet is disposed on an opposite side of the stay line from its initial position.

8. A sailboat fitting adapted to be connected between separated portions of a sail sheet or the like with each of the portions having an eye splice and adapted to receive a stay line, the fitting comprising a ring formed of a rela-

5
10

tively rigid material of good tensile strength substantially circular in cross-section and of uniform diameter throughout, said ring being elongated and having inner end radii dimensioned to accommodate the eye splices and having a gap formed substantially centrally on one side thereof dimensioned to closely receive the stay line therethrough so that the ring is effective to receive the stay line when moved thereagainst with the gap in register therewith and to release the stay line upon rotation of the ring through the eye splices so that the sheet is disposed on an opposite side of the stay line from its initial position.
